(57) **CLAIM**

The ornamental design for a bus bar unit for battery, as shown and described.

DESCRIPTION

FIG. 1 is a front perspective view showing the overall configuration of a bus bar unit for battery according to our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a bottom perspective view thereof;

FIG. 9 is an enlarged view showing a portion 9 of FIG. 1;

FIG. 10 is an enlarged view showing a portion 10 of FIG. 2;

FIG. 11 is an enlarged view showing a portion 11 of FIG. 3;

FIG. 12 is an enlarged view showing a portion 12 of FIG. 4;

FIG. 13 is an enlarged view showing a portion 13 of FIG. 5;

FIG. 14 is an enlarged view showing a portion 14 of FIG. 6;

FIG. 15 is an enlarged view showing a portion 15 of FIG. 7;

and,

FIG. 16 is an enlarged view showing a portion 16 of FIG. 8.

The unevenly spaced broken lines in FIGS. 1-16 highlight enlarged areas of the claimed design, and form no part of the claimed design.

1 Claim, 7 Drawing Sheets
